CLAIM

The ornamental design for a thermal imager, as shown and described.

DESCRIPTION

FIG. 1 is a top, front, right side perspective view of a thermal imager showing my new design in a first embodiment.

FIG. 2 is a bottom, rear, left side perspective view thereof.

FIG. 3 is a front elevation view thereof.

FIG. 4 is a right side elevation view thereof.

FIG. 5 is a top plan view thereof.

FIG. 6 is a rear elevation view thereof.

FIG. 7 is a left side elevation view thereof.

FIG. 8 is a bottom plan view thereof.

FIG. 9 is a top, front, right side perspective view of the thermal imager in a second embodiment.

FIG. 10 is a bottom, rear, left side perspective view thereof.

FIG. 11 is a front elevation view thereof.

FIG. 12 is a right side elevation view thereof.

FIG. 13 is a top plan view thereof.

FIG. 14 is a rear elevation view thereof.

FIG. 15 is a left side elevation view thereof; and,

FIG. 16 is a bottom plan view thereof.

The broken lines illustrate portions of the thermal imager that form no part of the claimed design. The dot-dash lines in FIGS. 1, 3, 7, and 15 define the bounds of the claimed design and form no part thereof. The stippling provides surface shading that merely clarifies contours of the surface and does not indicate surface texture, material, contrast in material, or color.
